UNITED STATES PATENT OFFICE.

JACOB BEUC, OF ST. LOUIS, MISSOURI.

BRACE ROD FOR CASEMENT WINDOWS.

Application filed January 23, 1928. Serial No. 248,787

The present invention has relation to improvements in casement window brace rods and consists in the novel features of construction more fully set forth in the specification and pointed out in the claims.

The principal object of the present invention is to provide a casement window brace rod that is extensible to permit the window to be opened to any predetermined degree where it may be securely held by merely moving a rotatable cam a slight degree for clamping the extensible rod in position. A further object is to provide adjustment for the clamping mechanism of the brace rods so as to take up play that results from wear. Further objects are to provide a brace rod that is positive in its action, one that is durable and one that may be manufactured at comparatively small cost. Further and other objects will be better apparent from a detailed description of the invention in connection with the accompanying drawings, in which:—

Figure 1 is a perspective view of a casement window showing my improved brace rod applied thereto; Fig. 2 is a middle longitudinal section taken through the assembled brace rod; Fig. 3 is an elevational view of the tube and clamping mechanism surrounding the rod or core of the device; and Fig. 4 is a cross-sectional detail taken on the line 4—4 of Fig. 2.

Referring to the drawings, it will be observed that my improved brace rod is formed of two members, a non-sliding casing A and a sliding rod B, one end of which is supported in said casing. The casing A has a swivel connection 1 with a bracket 2 that is adapted to be fixed on the sill S of window frame F. The outer end of rod B is pivotally connected to a bracket 3 which is securely fixed to a casement window W hinged in the frame F.

The outer end of casing A is provided with an annular shoulder 4 and the inner end is screw-threaded to receive a plug 5 having a head 6. Positioned within the casing A and in contacting relation with plug 5 is a ring cam 7 having its inner edge 8 cam-shaped to cooperate with the cam formation 9 formed on the adjacent edge of a sleeve 10 within casing A and extending through a considerable portion thereof. Between the outer edge 11 of sleeve 10 and shoulder 4 of casing A is arranged a series of clamping members comprising in the order named a

wedge ring 12, a fibre contracting ring 13, a wedge ring 14, fibre contracting ring 15, and a wedge ring 16. The fibre contracting rings 13 and 15 are split respectively as designated at 17 and 18 and their edges 19, 60 19 and 20, 20 respectively are bevelled to cooperate with sloping or inclined edges 21 of ring 12, 22, 22 of ring 14, and 23 of ring 16. The sleeve 10 is held against rotation by a set screw 24 traversing casing A and entering into slot 25 in sleeve 10, said slot permitting reciprocation of said sleeve but no rotation thereof. A slot 26 is provided in casing A, and a thumb screw 27 traverses said slot and is screwed into the ring cam 7, said slot 70 26 being of sufficient length to allow the thumb screw 27 to be oscillated back and forth and being somewhat wider than the shank of the thumb screw for a purpose hereinafter to become apparent.

When it is desired to open the window W, the cam 7 is rotated by means of thumb screw 27 in the direction of the arrow (Fig. 4) which releases any tension on the sleeve 10 and, of course, allows the fibre rings 13 and 80 15 to expand to their normal diameter, thus unclutching the rod B and allowing it to slide freely in the casing A. Having adjusted the window to the proper position, the cam 7 is rotated in the direction opposite to that indicated by the arrow (Fig. 4) whereby the cam-shaped edge 8 will force the sleeve 10 outwardly because of the co-action of the edge 8 and edge 9 of said sleeve and the inability of the sleeve 10 to rotate. The outward movement of sleeve 10 causes rings 13 and 15 to be squeezed together by the action of wedge rings 12, 14 and 16, said contraction of rings 13 and 15 firmly gripping the rod B and holding 85 said rod against any further longitudinal movement in the casing A. Obviously, after considerable use, the frictionally engaging parts of wedge rings and contraction rings are bound to wear and render the clutching action on the rod B less certain. I have, 90 therefore, provided the screw plug 5 which may be screwed further into the casing A to take up such play that results from wear. To permit the ring cam 7 to move further into the casing when the plug 5 is adjusted for 95 wear, there is clearance provided between the sides of slot 26 and thumb screw 27.

From the foregoing it will be seen that I have provided a brace rod that may be released or locked with but a very slight move- 110

ment of the actuating cam, and one wherein there is suitable provision made for overcoming play or lost motion due to wear.

Having described my invention, I claim:

5. 1. A brace rod for casement windows, or the like, comprising a tubular casing, a plurality of clutch members within said casing, a rod adapted for sliding movement within said casing, means for actuating the clutch members to grip and release said rod, and means for effecting adjustment for compensating against play due to wear.
10. 2. A brace rod for casement windows, or the like, comprising a tubular casing, a plurality of ring clutch members within said casing, a rod traversing the clutch members and adapted for sliding movement within said casing, and means for actuating the clutch members to grip and release said rod.
15. 3. A brace rod for casement windows, or the like, comprising a tubular casing, a sleeve adapted for longitudinal movement within said casing, a plurality of ring clutch mem-

bers confined between said sleeve and abutment at one end of the casing, a rod adapted for movement through the clutch members, and means for imparting longitudinal movement to the aforesaid sleeve for effecting a contraction of the clutch members to grip said rod.

25. 4. A brace rod for casement windows, or the like, comprising a tubular casing, a sleeve adapted for longitudinal movement within said casing, a plurality of ring clutch members confined between said sleeve and abutment at one end of the casing, a rod adapted for movement through the clutch members, a rotary cam adapted to cooperate with one end of the aforesaid sleeve to impart longitudinal movement thereto for actuating the clutch members, and an adjustable abutment for confining said cam.

30. In testimony whereof I hereunto affix my signature.

40. JACOB BEUC.
